Attorney

UNITED STATES PATENT OFFICE.

JACOB L. KAUFMANN, OF LOS ANGELES, CALIFORNIA, ASSIGNOR, BY DIRECT AND MFSNE ASSIGNMENTS, OF ONE-THIRD TO ALAN E. POST, ONE-THIRD TO MABEL B. CURTIS, AND ONE-SIXTH TO ETHEL A. KAUFMANN, ALL OF LOS ANGELES, CALIFORNIA.

HAIR-COLLECTING ATTACHMENT FOR CLIPPERS.

Application filed February 20, 1926. Serial No. 89,700.

My invention relates to and has for its purpose the provision of an attachment for hair clippers either manually or motor operated and used in the clipping of human hair or animal hair by which hair as it is clipped is removed from the vicinity of the clipper and conveyed to, for collection in, a remote receptacle, whereby the unhygienic conditions resultant of clipped hair and the labor involved in the clipping of the hair is eliminated.

It is also a purpose of my invention to provide an attachment of the above described character which employs air suction or what is commonly referred to as vacuum, for collecting the hair, my invention specifically involving the provision of a portable suction nozzle associated with a pair of clippers in such manner as to not interfere with the normal use of the clippers, yet effectively collecting all hair as it is cut by the clippers.

I will describe only one form of hair collecting attachment embodying my invention and one form of hair clipper, and will then point out the novel features thereof in the claim.

In the accompanying drawings,

Figure 1 is a view showing in side elevation one form of attachment embodying my invention in applied position to a pair of hair clippers;

Figure 2 is an enlarged view showing in longitudinal section and partly in elevation the nozzle of the attachment shown in Figure 1 with the clippers in applied position thereto;

Figures 3 and 4 are sectional views taken on the lines 3-3 and 4-4, respectively, of Figure 2.

Referring specifically to the drawings, in which similar reference characters apply to similar parts in each of the views, my invention, generically, embodies the broad combination of a hair clipper and a suction apparatus associated with the hair clipper to effectively collect cut hair as it is clipped by the clipper. In the present embodiment of my invention, the suction apparatus comprises a motor operated fan 15 rotatable in a casing 16 to which latter is connected a flexible pipe 17 and to a nozzle designated generally at N. The casing 16 is provided with a discharge 18 which is adapted for

connection with a suitable receptacle (not shown) into which is finally deposited the hair as collected by the apparatus.

The nozzle N comprises an elongated tubular body 19 formed of metal or other suitable material and having a relatively broad intake end 20, and a rounded discharge end 21, this latter end being connected to the pipe 17. The bottom side of the body 19 is substantially flat, as illustrated in Figure 3, and as shown in Figure 4 it is provided with a depending socket 22. This socket 22 is adjacent the discharge end of the body, while adjacent to the intake end a pair of arms 23 extend downwardly from opposite sides of the body with their free ends bent inwardly upon themselves to provide heads 24. These arms 23 are formed of resilient metal and they are adapted to co-operate with each other and with the heads 24 to form clips for detachably securing a pair of clippers to the under side of the nozzle body.

I have shown in Figures 1 and 2 a conventional pair of hair clippers comprising an elongated body 25, the rear end 26 of which is rounded, while the forward end carries the clipping blades 27. Extending into the rear end of the body is a flexible shaft 28 operatively connected to a motor 29 which may be suspended in elevated position as shown and which is adapted to operate the blades 27 of the clipper through the medium of the shaft 28.

In the applied position of the clipper to the nozzle, the rear end 26 is received in the socket 22, while the spring arms 23 embrace the body 25 at its opposite sides with the heads 24 securing the body against displacement from between the arms. In this manner, the arms function to retain the rear end of the clipper body in the socket 22 and to thus securely retain the clipper upon the under side of the nozzle body with the blades 27 disposed below and in advance of the intake end 20.

In practice, the operator grips the nozzle body in the manipulation of the clippers in the usual manner to effect clipping of hair, and during this clipping operation the hair which is clipped is sucked into the intake end of the nozzle and finally discharged into the remote receptacle connected to the discharge 18.

2

Because of the close proximity of the intake end of the nozzle with respect to the clipping blades, it will be manifest that as the hair is clipped it is immediately drawn into the nozzle, so that the possibility of the hair dropping from the clippers is positively prevented and thus all the hair is gathered and discharged to the receptacle by my apparatus. The mounting of the clippers on the nozzle permits of the ready attaching and detaching of the clippers to the nozzle so that both may be readily cleaned or repaired and either may be used independently.

15 Although I have herein shown and described only one form of hair collecting at-

tachment embodying my invention, and one form of clipper, it is to be understood that various changes and modifications may be made without departing from the spirit of the invention and the spirit and scope of the appended claim.

I claim as my invention:

In combination, a hair clipper having an elongated body, and an air suction nozzle 25 having a socket for receiving one end of the body, and clips engaging the clipper body and co-acting with the socket to retain the clipper on the nozzle with the blades of the clipper adjacent the intake end of the 30 nozzle.

JACOB L. KAUFMANN.
